(57) **CLAIM**

The ornamental design for a gas cylinder container, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front side view of a gas cylinder container in the closed position.

FIG. 2 is a side view thereof;

FIG. 3 is a rear view thereof;

FIG. 4 is another side view thereof;

FIG. 5 is a top plan view thereof;

FIG. 6 is a bottom plan view thereof; and,

FIG. 7 is a top perspective view thereof.
